UNITED STATES PATENT OFFICE.

HARRY G. BROWN, OF NORTH YAKIMA, WASHINGTON.

VALVE-GRINDING MACHINE.

1,233,022.

Specification of Letters Patent.

Patented July 10, 1917.

Application filed January 17, 1916. Serial No. 72,607.

To all whom it may concern:

Be it known that I, HARRY G. BROWN, a citizen of the United States, residing at North Yakima, in the county of Yakima and State of Washington, have invented certain new and useful Improvements in a Valve-Grinding Machine, of which the following is a specification.

An object of my invention is to provide 10 a valve grinding machine which may be used to grind one or to simultaneously grind a plurality of valves of one or more gas or explosive engines, the valve grinding mechanism being so constructed and arranged 15 that it may be used in a factory, garage, or repair shop, by being mounted on a stationary or portable support, or may be used to grind the valve or valves of a single engine by being mounted in conjunction with the 20 particular engine to be treated, and which also is so arranged that it may be mounted on a suitable support or frame in a relation to act upon the valves of the V-type of engine.

25 A further object is to so construct the parts that a resilient and yielding pressure is exerted upon each of the valves to hold the same against the seat in the grinding operation and to further arrange means by 30 which the valves are each permitted to be raised under the tension of a spring fitted around the stem at predetermined intervals to be again reseated and to thus avoid cutting or grooving of the valve and its seat, 35 this cutting or grooving of the fitting surfaces being occasioned by uneven distribution of the emery powder and oil or other abrasive material which is placed upon the valve seat.

40 A still further object lies in the construction and mounting of the valve engaging and turning bit and the parts associated therewith to cause operation of the same in such a manner that adjustment may be made 45 to adapt the machine to be used upon engines having the valves located at variously spaced points.

With the above and other objects in view, my invention consists in certain novel features of construction and combinations of parts which will be hereinafter set forth in connection with the accompanying drawings and then pointed out in the claims.

In the drawings:

50 Figure 1 is a view in side elevation of the completed machine.

Fig. 2 is a view in end elevation of the structure disclosed in Fig. 1, the view being taken from the driving end of the machine.

Fig. 3 is a detail top plan view to better 60 illustrate the bit turning means.

Fig. 4 is a detail perspective view of the shank end of one of the valve engaging bits.

Fig. 5 is a vertical sectional view through one of the bit sockets and the operating 65 barrel associated therewith.

Fig. 6 is a view in side elevation of the structure disclosed in Fig. 5 with the top broken away.

Fig. 7 is a view in perspective of the upper end of one of the barrels with a slightly modified form of operating means fitted thereto.

Fig. 8 is a transverse sectional view taken on the line 8-8 of Fig. 5.

Fig. 9 is a fragmentary detail view to show certain of the operating parts.

Fig. 10 is a detail sectional view taken through an engine cylinder with the valve illustrated as fitted preliminary to the grinding of the same.

The frame structure comprises the uprights 1 and 2 which are connected across by the cross bars 3 and 4 and it is preferable that each of the uprights 1 and 2 be constructed of two members which are provided with the right and left hand threads at 5 and 6 on the adjacent ends thereof, the internally screw-threaded sleeves 7 being provided to be received over these screw-threaded ends so that the proximity of the cross members 3 and 4 may be adjusted. It is preferable that the frame structure, that is, both the uprights and the cross bars be constructed of cylindrical tube metal and 85 at the lower end of each of the uprights bearings 8 and 9 are provided to have the cam shaft 10 revolvably mounted therein. The upper ends of the uprights 1 and 2 are offset, as is better illustrated in Fig. 2, and 95 at the ends of these offset portions, the bearings 11 and 12 are provided.

An operating shaft 13 is journaled across the frame in the bearings 11 and 12 and at the outer end of this operating shaft a driving gear is mounted. Power is transmitted to the driving shaft 13 through the medium of a crank handle 15, or if desired, a belt may be led over the belt pulley 16 on the shaft and the machine may be thus power 110 driven, the power operation being perhaps preferable where the machine is to be

- used by the manufacturer. A stub-shaft 17 is mounted at its inner end in a suitable bearing provided on the upright 2 and at its outer end is journaled in a bearing provided in the yoke or bracket member 18, and a gear wheel 19 is secured on this stub-shaft 17 to mesh with the gear 14 and to cause the turning of the stub-shaft as the operating shaft 13 is revolved.
- 10 A sprocket wheel 20 is secured on the outer end of the cam shaft 10 and a sprocket chain 21 is led over this sprocket wheel 20 and over a sprocket wheel 22 which is secured on the stub-shaft 17, power thus being transmitted by a more or less direct drive from the operating shaft 13 to the cam shaft 10.
- In the present disclosure, I have illustrated a machine which will simultaneously grind both the intake and exhaust valves of a four cylinder engine, and as is shown, there are eight operating wheels 23 mounted on the operating shaft 13. As is better illustrated in Fig. 1, the rims of these wheels are given a 10° to 15° incline from the angle at which the hubs are bored, and in this way the operating wheels 23 are made to take substantially a cam form. The operating shaft 13 has a key or spline 24 on one side thereof and the hub of each of the operating wheels 30 23 is provided with a key-way or slot to receive this spline so that the operating wheels will be held against turning movement on the operating shaft 13 but are capable of endwise sliding movement, the adjustment 35 of the same being set and maintained through the medium of the set screws 25 which are received through the hub to be brought to a bearing against the operating shaft 13.
- 40 In the use of this machine, the valves 26, as illustrated in Fig. 10, may be of the tapered type, or may close down against flat seat, the coil spring 27 fitted around the stem thereof to normally exert a tension to 45 hold the head of the valve out of contact with the valve seat 28, and the heads are slotted or kerfed across to provide the slotted opening 29 in which the end of the turning bit is received. It is the usual practice 50 in the manufacture of valves for explosive engines to provide this slot or kerf 29 in the head and for this reason my invention is adaptable to be used with substantially any type or make of explosive engine.
- 55 The turning barrels 30, now referring more particularly to Figs. 5 and 6, are provided with the flanges 31 and 32 which extend therearound at spaced apart points to receive the bearing rings 33, better illustrated in Fig. 8. These bearing rings 33 have lugs 34 provided from one side thereof and the lugs are bored through to receive the cross member 3 of the frame. The turning barrels 30 are revolvably mounted in the sleeves 33 and by adjusting these sleeves
- along the extent of the cross member 3, and then securing the same in place by means of set screws 35, the barrels may be mounted in a relation to correspond with the disposition of the valves of the engine and with the placing of the operating wheels 23.
- The shells 36 are made of a size to be revolvably fitted in the turning barrels 30 and if desired, the ball-bearings 37 may be fitted in the wall of the turning barrel to have contact with the shells 36 and to relieve any friction incident to the turning of the shell within the barrel. The socket members 38 are made to have a sliding fit within the shells 36 and are received therein, these socket members being provided with the slotted openings 39 through which pins 40 are received to mount the socket members to be capable of endwise sliding movement in the shells but to yet hold the same against turning movement with respect thereto.
- As is better shown in Fig. 9, the shells 36 have the lower ends thereof serrated to form the teeth 41 and externally screw-threaded sleeves 42 which are adapted to be screwed into the interiorly screw-threaded lower ends of the barrels 30, have the upper edges provided with serrations or teeth at 43 which teeth are made of a size and contour to fit and be engaged with the teeth of the shells 36. A plate or disk 44 is mounted on the upper end of each of the shells 36 and ball-bearings 45 are provided between this plate and a plate or disk 46 which is placed thereabove, a coil spring 47 being mounted in the upper end of the bore of each of the turning barrels 30 to bear against the upper closed ends thereof and against the plate 46 to normally exert a pressure to hold the shells 36 in a relation that the teeth 41 thereon are in mesh with the teeth 43 of the sleeve 42. A second coil spring 48 is mounted within the shell 36 to bear at its one end against the plate 44 and with its opposite end bearing against the upper end of the socket member 38 to exert a pressure to extend this socket member from the shell 36 and through the sleeve 42, the socket member being held against too great extension by reason of the fact that the pin 40 is fitted through the slotted opening 39 thereof.
- It is preferable that the socket members 38 have the sockets 49 thereof square or polygonal shaped in cross section and the turning bits 50 have the shank ends made of the same polygonal form, these shanks being provided with a plurality of orifices 51 in which the set screws 52 carried by the socket members 38 will engage to hold the bit members 50 in a predetermined extension. The bit members 50 are wide and flattened out at their lower ends to provide the valve engaging ends 53, and it will of course be understood that these ends 53 will be made 130

to fit and be received within the slotted openings 29 provided in the head of the valve 26. Collars 54 are mounted around the socket members 38 and are fitted thereto to permit turning and sliding movement, these collars being provided with the bearing portions 55 which are received around the cross members 4 and the set screws 56 being mounted through these bearing portions to engage with the cross member 4 to hold the collars 54 in the proper relation to guide and support the socket members 38 at their lower ends. It is preferable that the screws 57 be provided to be turned into threaded orifices provided between the barrel 30 and the sleeve 42 to prevent displacement of the sleeve from its fitted position within the lower end of the turning barrel and in this way and through the medium of the bearing sleeves 38 and the collars 54, the turning barrels 30 are mounted to be capable of rotating or oscillating movement while the socket members 38 are mounted to be normally carried with the turning barrel and when sufficient upward tension is exerted thereon to overcome the spring 47 to be moved to a position that they may have turning movement independent of the barrels 30, or that the barrels 30 may be turned independently of these socket members.

Each of the socket members 38 has an annular rim or flange 58 provided near the lower end thereof, and it is preferable that these rims or flanges be given a relatively great extent from the socket members. The cam shaft 10 has a spline or key 59 extending throughout the great part of the length thereof and the cam members 60 are fitted on this shaft to be capable of sliding along the length thereof, these cam members being provided with key-ways to receive the spline 59 and the set screws 61 being passed therethrough to engage with the shaft to set the cams in the desired operating relation. Each of the cams 60 is provided with an offset bearing portion 62 and thus as the cam is brought under the annular rim 58 of each of the socket members 38, this bearing extension 62 will engage with the lower side of the annular rim 58 and will cause the socket member 38 to be raised sufficiently that the pin 40 will be engaged against the bottom of the slotted opening 39 and through the connection of this pin 40, with the shell 36, the shell will be caused to be raised against the tension exerted by the coil spring 47 and consequently, the teeth 41 thereof will be disengaged from the teeth 43 on the sleeve 42. It is of course understood that the socket member 38 has upward movement against the tension of the spring 48 and thus as the extension 62 passes from beneath the annular rim 58, the socket member 38 will be permitted to again move downwardly

comparatively instantaneously under the tension exerted by the springs 47 and 48.

The heads of the turning barrels 30 have the notches or grooves 63 formed therein preferably at one side of the center, this feature being better illustrated in Fig. 3, and the extension of the upper end of the uprights members 1 and 2 on which the bearings 11 and 12 are carried are carried to a point that the operating shaft 13 is not directly over the turning center or vertical axis of the turning barrel 30, but is rather at a point to one side and beyond the turning center or axes of the same. The operating wheels 23 are received on their lower sides in the notched out or recessed openings 63 and as the operating shaft 13 is turned, the angular disposition of the rims of the operating wheels 23 and the fitting of the same to the notches or recesses 63, will cause the turning barrels 30 to have an oscillatory movement.

The supporting or mounting arms 64 are disposed in a substantially V-shaped formation from the upright members 1 and 2 and the extension members 65 which are adjustably and telescopically mounted on the lower ends of the supporting members 64 have a plurality of openings 66 provided therethrough to be in alignment with a single opening formed through the lower end of the supporting members 64 and by passing the bolts or other fastening means 67 through one of the openings of the adjusting members 65 and the opening of the adjusting member 64, these supports in their entirety may be made of the proper length to permit fastening means to be mounted through the orifices 68 provided in the lower end of the extension member 65 and thus the framework may be mounted and supported in the proper operative relation upon the engine structure.

In the disclosure in Fig. 7, I have shown in lieu of the notches or recesses 63, a pair of spaced apart pins or studs 69 positioned at one side on the head of the barrel to have the rim of the operating wheel 23 received therebetween and to be engaged by these rims as the operating shaft 13 is rotated to cause the oscillatory movement to be imparted to the turning barrels 30.

In the use of the machine, the bearings 33 and the collars 54 are adjusted along the transverse members 3 and 4 to such a position, that the engaging ends 53 of the bit members 50 will come within the notch opening of the valve head and then are secured in the proper relation by tightening the set screws 35 and 56, it being of course understood that the operating wheels 23 have the set screws 25 thereof loosened so that these operating wheels may be adjusted along the operating shaft 13 with the turning barrel 30, and that when the parts have

been brought to the proper operative relation, the set screws 25 will be tightened to hold the operating wheels in the proper mounting. In the present instance I have disclosed the cams 60 as being disposed alternately in a diametrically opposite relation as this positioning of the cams will bring the bit members 50 into and out of the position where the valves are engaged in the grinding relation, in such a manner that less strain will be placed upon the operating parts and less power is required to drive each of the gang of grinding means. The valves are fitted in accordance with the disclosure of Fig. 10 and the abrasive material is placed upon the bearing surfaces of the valve and its seat, the ends of the bit members are fitted in the grooves in the valve head and the proper adjustment and securement of the frame structure upon the engine is made through the mounting members 64 and 65. A further adjustment may be obtained through the medium of the threaded sleeve 7 and when the parts have each been brought to the proper adjusted relation, turning of the operating shaft 13 through the medium of the handle 15 or through a belt led over the driving pulley 16 will cause the operating wheels 23 to be turned and through their engagement with the heads of the turning barrels 30 will impart an oscillatory movement to these turning barrels. It is preferable that the gear 19 be made approximately twice the size of the driving gear 14 and that the same ratio be observed between the front wheels 22 and 20 so that the cam shaft 10 will be turned at a slower speed than the operating shaft 13 as it is not desirable that the valve be permitted to raise from its seat at the end of each movement of the reciprocatory travel of the barrel 30 or even at the completion of the forward and back oscillatory movement of the same. As the springs 47 and 48 act to hold the valve 26 down against the seat 28 through overcoming of the tension of the spring 27, and also to cause the teeth 41 to be engaged with the teeth 43, the socket members 38, the bits 50 and consequently the valves are turned, the valves being given a reciprocatory movement within or against the seats 28 and through the fact that an abrasive material is spread in a layer or film therebetween, accomplishing a grinding action and forming a new surface on both the valve and the seat. A continuation of this oscillatory movement of the valve against the seat without varying the relative bearing thereagainst will cause the valve or the seat, or both, to become grooved or cut due to the fact that it is practically impossible to obtain an even and uniform distribution of the abrasive material over all parts, and to overcome this objection, the cams 60 are provided to raise the socket members 38 to a position that the valves 26 are permitted to rise from engagement against the seats 28, at the same time, the teeth 41 are disengaged from the mesh with the teeth 43, permitting the turning barrels 30 to have movement independent of the shells 36 and the socket members 38. In this way the next meshing of the teeth 41 and 43 is in a varied relation from that meshing from which they have been unseated, and in consequence the relative disposition of the valves 26 against the seats 28 is varied and through a better and more equal distribution of the abrasive material by the shifting of the valves, any tendency toward cutting or grooving is materially relieved if not entirely overcome.

While I have herein shown and described only one specific form of my invention, it will be understood that various modifications in the form of the mounting, in the arrangement of the parts to permit the adjustment thereof, and in other features of the invention might be resorted to without departing from the spirit and scope of my invention, and hence I do not wish to be limited to the exact disclosure but only to such points as may be set out in the claims.

I claim:

1. A valve grinding machine comprising a turning barrel, an operating wheel mounted in conjunction with said turning barrel to impart oscillatory movement thereto when turned, means by which a valve is coupled to move with the turning barrel, means to raise the valve coupling means to permit the valve to be unseated and to reseat in a varied relation, and power means to simultaneously turn the operating wheel and actuate the means by which the valve coupling means is raised. 95
2. A valve grinding machine comprising a turning barrel having a clearance space at the top thereof for reception of an operating wheel, a shaft mounted above said turning barrel, an operating wheel obliquely disposed and fixed upon said shaft and received in the recess provided in the top of the turning barrel, means connected with the turning barrel to engage with and hold a valve to be turned and moved therewith, and means to impart revoluble movement to the shaft to accomplish oscillatory movement of the turning barrel through the action of the obliquely disposed operating wheel. 110
3. A valve grinding machine comprising a turning barrel, an operating wheel to be turned to impart an oscillatory movement to the turning barrel, means connected with the turning barrel, to engage with and hold a valve to be turned therewith, means to raise the valve engaging means to permit the valve to be unseated and to reseat in a varied relation as the oscillatory movement of the turning barrel is continued, means to adjust 125

the parts to be mounted in the proper operative relation upon the valve carrying mechanism, and power means to cause the simultaneous driving of the operating wheel, and the means by which the valve is unseated.

4. A valve grinding machine comprising a frame structure, a plurality of turning barrels mounted on the frame structure, turning bits carried by the said barrels to engage with the valves of an engine, springs mounted within the turning barrels to exert bearing pressure to normally hold the bit extended therefrom, operating wheels by which turning movement is imparted to the turning barrels in a reciprocatory path to cause the valve to be ground against its seat, and means by which each turning bit is raised against the bearing pressure of the springs to such an extent that the valve is permitted to be raised from its seat and re-seated in a varied relation.

5. A valve grinding machine comprising a frame structure, a plurality of turning barrels mounted on the frame structure, turning bits carried by the said barrels to engage with the valves of an engine, operating wheels by which turning movement is imparted to the turning barrels in a reciprocatory path to cause the valve to be ground against its seat, means by which the valve is permitted to be raised from its seat and re-seated in a varied relation, and driving means by which turning movement is imparted to the operating wheels and actuation movement is imparted to the valve releasing means at a relatively lower speed.

6. A valve grinding machine comprising a supporting frame structure, a plurality of turning barrels mounted on said structure, turning bits carried by said turning barrels to engage with and hold the valves of an engine, an operating shaft, and a plurality of operating wheels mounted on said operating shaft and having the rims thereof disposed at an angle and engaged with the turning barrels to cause the same to have oscillatory movement as the operating shaft is turned.

7. A valve grinding machine comprising a supporting frame structure consisting of uprights and a pair of spaced apart cross bars, an operating shaft mounted in bearings provided at the upper end of said uprights, turning barrels supported on one of said cross bars to be capable of turning movement, turning bits carried by the turning barrels to be engaged with and hold the valves of an engine, means by which the turning barrels are adjusted and set to the proper relation to engage with the valves, said turning barrels provided with a groove at one side on the head thereof, and operating wheels having the rims thereof disposed at an angle and received in the grooves of the turning barrels to cause the turning barrels to have oscillatory movement as the

operating shaft is revolved and to impart this movement to exert a grinding action between the valves and their seats.

8. A valve grinding machine comprising a supporting frame structure consisting of uprights and a pair of spaced apart cross bars, an operating shaft mounted in bearings provided at the upper end of said uprights, turning barrels supported on one of said cross bars to be capable of turning movement, turning bits carried by the turning barrels to be engaged with and hold the valves of an engine, means by which the turning barrels are adjusted and set to the proper relation to engage with the valves, said turning barrels provided with a groove at one side on the head thereof, operating wheels having the rims thereof disposed at an angle and received in the grooves of the turning barrels to cause the turning barrels to have oscillatory movement as the operating shaft is revolved and to impart this movement to exert a grinding action between the valves and their seats, a cam shaft connected in bearings provided at the lower end of the frame upright, and cams arranged to become operative upon rotation of said cam shaft to permit the valve to be unseated and to be reseated in a varied relation.

9. A valve grinding machine comprising a frame structure consisting of a pair of upright members with cross bars disposed therebetween in a spaced relation, turning barrels rotatably mounted on the upper of said cross bars to be adjustable along the length thereof, socket members mounted in collars adjustably carried on the lower of said cross bars to be normally carried with the turning barrels and to be capable of endwise sliding movement therein, turning bits adjustably carried within the socket members and disposed to be engaged with and hold the valves of an engine, an operating shaft mounted across the uprights near the upper ends thereof, said turning barrels provided with recessed portions, and operating wheels having the rims thereof disposed at an angle mounted on the operating shaft to have the said rims received in the recessed portions and as the operating shaft is turned to impart an oscillatory movement to the turning barrels and consequently to the valves.

10. A valve grinding machine comprising a frame structure consisting of a pair of upright members with cross bars disposed therebetween in a spaced relation, turning barrels rotatably mounted on the upper of said cross bars to be adjustable along the length thereof, socket members mounted in collars adjustably carried on the lower of the cross bars to be normally carried with the turning barrels and to be capable of endwise sliding movement therein, turning

bits adjustably carried within the socket members and disposed to be engaged with and hold the valves of an engine, an operating shaft mounted across the uprights near the upper ends thereof, said turning barrels provided with recessed portions, operating wheels having the rims thereof disposed at an angle mounted on the operating shaft to have the said rims received in the recessed portions, and as the operating shaft is turned to impart an oscillatory movement to the turning barrels, and consequently to the valves, a cam shaft mounted between the upright members at the lower ends thereof, annular shoulders disposed from said socket members, and cams carried by the said cam shaft to engage with the annular shoulders to raise the socket members and consequently the turning bits to a relation that the valves are released from their seated positions and are reseated in a varied relation during the grinding operation.

11. A valve grinding machine comprising a frame structure consisting of a pair of upright members with cross bars disposed therebetween in a spaced relation, turning barrels rotatably mounted on the upper of said cross bars to be adjustable along the length thereof, socket members mounted in collars adjustably carried on the lower of the cross bars to be normally carried with the turning barrels and to be capable of endwise sliding movement therein, turning bits adjustably carried within the socket members and disposed to be engaged with and hold the valves of an engine, an operating shaft mounted across the uprights near the upper ends thereof, said turning barrels provided with recessed portions, operating wheels having the rims thereof disposed at an angle and mounted on the operating shaft to have the said rims received in the recessed portions, and as the operating shaft is turned to impart an oscillatory movement to the turning barrels and consequently to the valves, a cam shaft mounted between the upright members at the lower ends thereof, annular shoulders disposed from said socket members, cams carried by said cam shaft to engage with the annular shoulders to raise the socket members and consequently the turning bits to a relation that the valves are released from their seated positions and are reseated in a varied relation during the grinding operation, power means by which movement is imparted to the operating shaft and at a relatively lower speed to the cam shaft, and means by which the machine may be mounted and supported in the proper relation upon an engine structure.

turning bits to a relation that the valves are released from their seated positions and are reseated in a varied relation during the grinding operation, and power means by which movement is imparted to the operating shaft and at a relatively lower speed to the cam shaft.

12. A valve grinding machine comprising a frame structure consisting of a pair of upright members with cross bars disposed therebetween in a spaced relation, turning barrels rotatably mounted on the upper of said cross bars to be adjustable along the length thereof, socket members mounted in collars adjustably carried on the lower of said cross bars to be normally carried with the turning barrels and to be capable of endwise sliding movement therein, turning bits adjustably carried within the socket members and disposed to be engaged with and hold the valves of an engine, an operating shaft mounted across the uprights near the upper ends thereof, said turning barrels provided with recessed portions, operating wheels having the rims thereof disposed at an angle mounted in the operating shaft to have the said rims received in the recessed portions and as the operating shaft is turned to impart an oscillatory movement to the turning barrels and consequently to the valves, a cam shaft mounted between the upright members at the lower ends thereof, annular shoulders disposed from said socket members, cams carried by said cam shaft to engage with the annular shoulders to raise the socket members and consequently the turning bits to a relation that the valves are released from their seated positions and are reseated in a varied relation during the grinding operation, power means by which movement is imparted to the operating shaft and at a relatively lower speed to the cam shaft, and means by which the machine may be mounted and supported in the proper relation upon an engine structure.

In testimony whereof I affix my signature in presence of two witnesses.

HARRY G. BROWN.
